UNITED STATES PATENT OFFICE.

EDWARD B. CRAFT, OF HACKENSACK, NEW JERSEY, ASSIGNOR TO WESTERN ELECTRIC COMPANY, INCORPORATED, OF NEW YORK, N. Y., A CORPORATION OF NEW YORK.

SOUND REPRODUCTION.

Application filed August 1, 1923. Serial No. 655,038.

To all whom it may concern:

Be it known that I, EDWARD B. CRAFT, a citizen of the United States of America, residing at Hackensack, in the county of Bergen and State of New Jersey, have invented certain new and useful Improvements in Sound Reproductions, of which the following is a full, clear, concise, and exact description.

10 The present invention relates to the reproduction of sound from sound records.

Among the objects of the invention are:

To secure high quality in sound reproduction;

15 To provide for any desired volume of reproduced high-quality sound;

To distribute the reproduced sound as may be desired.

The above and other objects of the invention and the means for realizing them in practice will be made clear in the following description in connection with the accompanying drawings.

In the drawings,

20 Fig. 1 is a schematic diagram, partly in plan view, of a sound reproducing system according to the invention.

Fig. 2 is a detail view.

25 Fig. 3 shows a modified form of reproducer.

Briefly and specifically described, the invention comprises translating the sound undulations in a record into variations in light, translating the light variations into electrical variations, and reproducing sound from the electrical variations after they have been amplified to any desired extent and distributed to any desired point or points.

30 The light variations may be produced by deflecting a beam of light by a mirror actuated by the usual reproducer needle when the needle passes over the sound record or vice versa. Since the mirror and its actuating mechanism may be made to have extremely small mass the light variations may represent to a high degree of accuracy, the recorded undulations. The light variations produce with high accuracy equivalent electrical variations, and these, in turn, may readily be amplified with negligible distortion to the desired volume and distributed as desired. At the point or points where the sound is to be produced, the usual loud-

speaking telephone apparatus may be employed.

Referring now to the drawings, the record 1 is rotated in the usual manner beneath the reproducer needle 2, which is mounted on the end of the arm 3 so as to be capable of freely swinging across the record the requisite extent. Arm 3 is pivotally mounted at 4 and at 5 so as to permit of movement of the needle both in the plane of the record and perpendicular to the record. 55 These parts are shown in plan in Fig. 1, and the sound undulations in the record are assumed to be lateral so that the needle vibrates back and forth in the horizontal direction. The needle and its clamping member are mounted to oscillate with respect to the arm 3 about a vertical axis 6. Springs 7 may be provided to constrain the needle toward a normal or equilibrium position substantially as shown. 75

80 Suitably secured to the needle mounting and adapted to partake of the needle movements, is a small mirror 8 for reflecting a beam of light from source 9 to the photo-electric cell 10 or other electro-responsive light-sensitive device. The light 9, telescope 14 and cell 10 are mounted on the arm 3 so that they swing with it. The cell 10 is enclosed in a box 11 which has a slit 12 in the side toward the mirror. This slit is arranged in conjunction with the rest of the optical system so that deflections of the light beam produce variations in the amount or intensity of illumination of the cell 10. For example, as shown in Fig. 2, the light beam, 85 indicated by the shading, may overlap the slit 12 any desired extent when the needle is in its central or equilibrium position. Deflection of the needle in either direction will then vary the illumination of the cell. 90

95 The electrical effects produced between the electrodes of the cell 10 are impressed on the amplifier A diagrammatically indicated in Fig. 1. It will be understood that any desired number of stages of amplification may be employed in addition to the single amplifying tube shown, so as to give any desired volume to the reproduced sound. The amplified current variations may be used to actuate a loud-speaking telephone receiving instrument 13, or any number of such instruments, connected either in parallel or in series with each other in any

usual or desirable manner. The instrument 13 or amplifier A or both may be positioned at a distance from the cell 10, and in case more than one loud speaker 13 is used, these may be distributed in any desired locations.

The optical system and sound record will, of course, be suitably enclosed in a light-tight chamber.

10 In operation, the light producing system is adjusted to give a properly shaped beam and the cell 10 is properly positioned by the aid of the adjusting screw 15. These 15 adjustments are preferably such that when the needle 2 occupies the position which it has when traversing a groove free of undulations, the light beam will overlap slit 12 to a considerable extent. As the record rotates, the needle traverses the spiral groove 20 maintaining the beam in this position except as it is deflected by undulations in the record groove. The deflections vary the illumination of the cell 10, setting up electrical variations which faithfully follow 25 the recorded sound variations, and when amplified and conveyed to receiver 13, reproduce sound of a desired volume and of high quality.

It will be noted that a very material amplification is obtained by the use of the light beam in the above-described manner, since 30 a very small movement in the mirror 8 produces a large displacement in the beam incident on the photo-electric cell. This also 35 makes for high quality of reproduction since the amplitude through which the mirror oscillates can be extremely small, in fact it can be made smaller than that of the needle-point itself.

40 In Fig. 3, the mirror 8 is shown mounted on the end of a relatively long arm 16 for the purpose of making the deflections in the reflected beam appear principally as translatory rather than rotary movements. 45 In certain types of optical systems or with special cells 10, and particularly where the cell is close to the mirror, this type of mounting may be preferable.

It will be obvious from the foregoing description to adapt the invention to records having "hill and dale" undulations by merely pivoting the mirror 8 by a horizontal axis and correspondingly modifying the light system, including slit 12.

50 The invention is applicable to other types of records than disk records, and is capable of various alterations and modifications from the specific construction shown, the scope of the invention being defined in the 55 claims.

What is claimed is:

1. In a sound reproducer, a record having a record groove containing undulations representing sound, an oscillation member 65 mounted so as to be free to oscillate about

an axis, means to produce relative movement between said record and said member to bring successive portions of the sound record into operative relation with said member, and to cause oscillations of said member in accordance with the recorded sound undulations, a light-sensitive, electro-responsive element, means to throw a beam of light from said oscillation member to said element, and to vary the illumination 75 of said element by said beam in accordance with the actuation of the member by the sound undulations, means to make the variations in illumination of said element independent of the position of said axis with respect to said record, and means to produce sound from the resultant electrical effects in said element.

2. In a sound reproducer, a record having a record groove containing undulations representing sound, an arm adapted to swing over said record, a reflector carried on said arm and mounted so as to be free to oscillate with respect to said arm about an axis, a source of light, a light-sensitive, electro-responsive element, said reflector being positioned so as to illuminate said element with reflected light from said source, means to produce relative movement between said record and said reflector to bring successive portions of said sound record into operative relation with said reflector, and to cause oscillations of said reflector about said axis in accordance with said undulations, the illumination of said element by the reflected light thereby varying in accordance with said sound undulations on said record, said axis of oscillation, said source and said element being positioned with respect to each other so that the variations in the illumination of said element are independent of the position of said arm over said record, and means to produce sound from the electrical variations in said element resulting from the variation in illumination.

3. In combination, a record having a record groove containing undulations representing sound, a reflector, an arm carrying said reflector and adapted to swing over the surface of said record, said reflector being mounted so as to be free to oscillate with respect to said arm about an axis perpendicular thereto, a source of light and a light-sensitive electro-responsive element mounted on said arm so as to swing therewith, said reflector being positioned so as to reflect light from said source to said element, means to produce relative movement between said record and said reflector to bring successive portions of the record into operative relation with said reflector, and to actuate said reflector in accordance with the recorded sound undulations, the illumination of said element by reflected light from said source thereby varying in accordance with the 13

sound undulations on said record, means to amplify the resultant electrical variations in said element, and means to produce sound from the amplified electrical variations.

5 4. In combination, a disc record having undulations representing sound recorded on the surface thereof, a stylus adapted for engagement with said undulations, an arm carrying said stylus and adapted to swing 10 in an arc over the surface of said record, said stylus being mounted on the free end of said arm so as to oscillate with respect to said arm about an axis thereon, said arm being pivotally mounted so as to permit 15 movement of said stylus both in the plane of the surface of said record and at an angle thereto, a reflector secured to said stylus and partaking of its movements, a source of light rays and a light sensitive, electro-re- sponsive element mounted on said arm so as 20 to swing therewith, said reflector being positioned so as to reflect a beam of light from said source to said element, means to rotate said record so as to bring successive portions of said recorded undulations into operative 25 relation with said stylus to cause oscillations of said reflector in accordance with said undulations, thereby varying in accordance with the sound undulations on the record, the amount of reflected light from said 30 source falling on said device, means to amplify the resultant electrical variations in said device, and means to produce sound from said electrical variations.

In witness whereof, I hereunto subscribe 35 my name this 30th day of July A. D., 1923.

EDWARD B. CRAFT.
